CABLE SPACER

Lee M. Watson, South Bend, Ind., assignor to Empire
Electric Corporation, Lakeville, Ind., a corporation of Indiana

Filed Mar. 26, 1964, Ser. No. 79,213

Term of patent 14 years

(Cl. D54—1)

FIG. 1

FIG. 2

FIG. 3

FIG. 4

FIG. 5

The broken line showing of cables is for illustrative purposes only.

I claim:

The ornamental design for a cable spacer, substantially as shown and described.
